UNITED STATES PATENT OFFICE

147,924

DESIGN FOR AN ANDIRON

Harriett E. Noble, San Francisco, Calif.

Application April 11, 1946, Serial No. 128,475

Term of patent 3½ years

(Cl. D81—6)

To all whom it may concern:

Be it known that I, Harriett E. Noble, a citizen of the United States of America, residing at San Francisco, in the county of San Francisco and State of California, have invented a new, original, and ornamental Design for an Andiron, of which the following is a specification, reference being had to the accompanying drawing, forming a part thereof.

Fig. 1 is a front elevational view of an andiron, showing my new design; and

Fig. 2 is a side elevational view thereof.

I claim:

The ornamental design for an andiron, substantially as shown.

HARRIET E. NOBLE.
